UNITED STATES PATENT OFFICE.

JOHN READING, OF AKRON, OHIO, ASSIGNOR TO THE READING MANUFACTURING COMPANY, OF SAME PLACE.

SAMPLE-BOOK RACK.

SPECIFICATION forming part of Letters Patent No. 527,809, dated October 23, 1894.

Application filed February 5, 1894. Serial No. 499,064. (No model.)

To all whom it may concern:

Be it known that I, JOHN READING, a citizen of the United States, residing at Akron, in the county of Summit and State of Ohio, 5 have invented a certain new and useful Improvement in Sample-Book Racks, of which the following is a specification.

In the wall-paper business as now conducted each manufacturer produces a series of 10 designs for the different classes and kinds of wall paper, and furnishes to the retail dealers sample books of the different papers. The preservation of these books from injury in handling, and the ability to readily produce 15 the samples from any particular manufacturer, and exhibit them are of the utmost importance to the retail dealer.

The object of my invention is to provide a 20 rack in which the sample books of different manufacturers may be suspended in close proximity to each other; from which any book may be readily removed and replaced; and which will afford tablets by which the names of the manufacturers and classes of paper 25 may be instantly ascertained.

To the aforesaid object my invention consists in the peculiar and novel construction, arrangement and combination of parts hereinafter described and then specifically pointed 30 out in the claim, reference being had to the accompanying drawings forming a part of this specification.

In the accompanying drawings in which 35 similar reference numerals indicate like parts in the several views: Figure 1, is a perspective of my complete rack; Fig. 2, a central, longitudinal vertical section of the right end of Fig. 1; and Fig. 3, an enlarged elevation of a portion of one of the suspension bars and 40 with its rocking brackets.

Referring to the drawings, 1 is a frame consisting of four posts united by side and end rails, to one of the narrower upper ends of

which is hinged a swinging slatted leaf 2, arranged to swing outward and be supported 45 by the brace 3, resting against the rack 4.

In the upper side rails of the frame 1, are pivotally suspended in oppositely-disposed sockets a series of rocking arms or brackets 5, each pair sustaining and connected with a 50 cross-bar 6, bearing in its center a knob 7, for a purpose to be stated. Each bracket bears a pintle to enter the socket in the side of the frame, and is connected with the cross bar 6, by a screw or equivalent device as 55 shown in Fig. 3, and they are arranged so nearly together that the adjacent cross bars will meet when rocked in either direction; but will separate when rocked in opposite directions, as shown in Figs. 1 and 2. On the 60 knobs 7 of each cross bar is hung the loop of one of the sample books 8. These books are inserted between the cross-bars 6, by swinging the adjacent bars apart; and when desired for exhibition are readily released therefrom by the same process; and, the suspending cord being looped over the knob 9, on the top of the leaf 2, allows the book to lie on said leaf, where its different patterns may be exhibited. 70

Having thus described my invention, what I claim, and desire to protect by Letters Patent, is—

A sample book rack consisting of a supporting frame, and parallel cross bars interposed between its sides, said cross-bars being mounted on rocking brackets pivotally mounted in the opposite sides of said frame, substantially as shown and described. 75

In testimony that I claim the above I here- 80 unto set my hand.

JOHN READING.

In presence of—
C. P. HUMPHREY,
R. A. MYERS.
